UNITED STATES PATENT OFFICE.

THEODOR BACHOFEN, OF WEST HOBOKEN, NEW JERSEY.

PILE-CUTTER KNIFE.

Application filed April 4, 1922. Serial No. 549,389.

To all whom it may concern:

Be it known that I, THEODOR BACHOFEN, a citizen of the United States, residing in West Hoboken, in the county of Hudson and 5 State of New Jersey, have invented certain new and useful Improvements in Pile-Cutter Knives, of which the following is a specification.

This invention relates to pile fabric cutting knives, as used in connection with looms for weaving and cutting the pile for floats, as formed over wires which extend in the direction of the warp and above the firmer woven base layer or portion of the fabric.

15 One of the objects is to provide a series of knives for cutting the loosely confined or floating filler threads at a point adjacent the lay as the weaving progresses.

Another purpose is to provide knife 20 blades which are readily independently removable from their holders for sharpening or other purposes.

A further aim is in the production of a series of knife holders, each being engaged 25 with a single wire operated by the harness and which may be disengaged in an instant without damage to either the holder or wire.

A still further object is to provide means 30 for reciprocating or oscillating each blade in its holder to produce a positive slitting or cutting effect independently of the reed action sometimes relied upon in beating the filler threads at each pick.

With these ends in view the invention consists in certain details of construction and 35 arrangement of parts hereafter described in detail and illustrated in the accompanying drawings forming a material part of this disclosure, and in which:—

40 Figure 1 is a plan view showing a fragmentary series of knives embodying the invention.

Figure 2 is an enlarged longitudinal sectional view taken on line 2—2 of Fig. 1.

45 Figure 3 is a similar sectional view but showing the knife blade in a forward or cutting position.

Figure 4 is a side elevational view of the blade in detail.

50 Figure 5 is a perspective view of the holder used therewith.

Figure 6 is a transverse sectional view taken on line 6—6 of Fig. 2.

55 Throughout the several views of the wires, designated by the numeral 20, will be understood by those skilled in the art to be the

"woven in" wires, which pass between the dents of the reed and thence certain of the heddles, beyond which they are tensioned in any preferred manner, and are operated with 60 the shed of the loom for the passage of the shuttle.

It is to be noted that a single strand of wire is used, not doubled at any point in its length, its free end extending beyond the 65 knives to any preferred distance where it is convenient of access in connecting or disconnecting the knife.

Arranged on each side frame of the loom are brackets (not shown) in which is fixedly 70 secured a transverse support rod 21 and a laterally movable rod 22, as will later be seen, is arranged in the same plane.

In this invention the holder, shown best in Fig. 5, is formed from a symmetrical sheet 75 metal blank bent to produce two equal sides 25 connected by a base 26 and having between them a narrow uniform space 27.

The upper edges of the sides may be straight and parallel with the base, but are 80 preferably formed with recesses 28 rendering the blade readily accessible.

The front edges 50 of the holder are formed obliquely downward, then continued forward at lesser angles 51 to 85 small convex curves 52 extending down to the base 26, said base projecting outward to its curved termination and containing a small opening 34 through which one of the wires 20 may be engaged. A circular opening 90 35 is formed through both of the holder sides 25, at its rear fitting the rod 21, and a slotted opening 36 near the front receives the rod 22.

The bar 53, disposed so as to rest on the 95 upper edges of the knives above the holder, slots 36, has lugs 54 at its ends on the lower side, engaging the rod 22 and on the upper surface are lugs 55 suited to receive connecting rods (not shown) by which the 100 bar 53 is oscillated.

The knife blade 56 is formed with a recess 57 in its lower edge 58, suited to rock on the rod 22 and its upper edge 59 extends straight from the heel or rear end 60, 105 to the rounded point 61 from which the cutter blade 62 extends obliquely to one side of the recess 57, said edge 62 being bevelled to both sides, as at 63, wholly or partially along its length.

110 In operation, when the cutter blade 62 is rocked or oscillated so that its upper

edge 59 is substantially paralleled with the base 26, the thread or threads 46 are moved upon the edge surfaces 51, as shown in Figure 2 and as the cutter blade is rocked into the position shown in Figure 3, they will be severed. At the same time the blade is moved rearwardly in its holder, due to the movement of the rod 22 as acted upon by the bar 53, giving a cutting effect that is positive in its operation.

As changes of construction could be made within the scope of the invention, it is intended that all matter contained in the foregoing description or shown in the accompanying drawings shall be interpreted as illustrative and not in a limiting sense.

Having thus described my invention, what I claim as new and desire to secure by Letters Patent, is:

- 20 1. A pile cutting device comprising a U shaped holder, having an oblique front end, including a portion substantially parallel to its base, a pair of spaced support rods passing through said holder, a knife blade 25 having an oblique cutting edge arranged in cooperative relation to the angle of said holder, said blade containing a recess engageable with one of said rods in such manner as to be supported by it, a flat bar 30 disposed transversely over said blade, lugs on said flat bar journaled on the last named rod, and means for oscillating said bar whereby said knife is rocked upon its rod support.
- 35 2. A pile cutting device comprising a pair of support rods, a plurality of knife holders having transverse openings suited to slidably engage said rods, the sides of said holders inclined downward at their 40 advance ends, blades closely engaged in said holders, said blades being shaped to present their cutting edges outwardly beyond the edges of said holders or be retracted therewithin, means for reciprocating said blades 45 relative to said holders, guard extensions on said holders adapted to guide material and maintain it in position to be severed upon the advance of said blades, and means

in said holders for engaging longitudinal warp wires in the fabric to be cut.

3. A pile cutting device comprising a pair of support rods, a plurality of knife holders having transverse openings suited to slidably engage said rods, the sides of said holders inclining downward at their 50 advance end, blades suited to operate in said holders, said blades rocking on one of said rods, means for oscillating said blades, cutting edges on said blades arranged in cooperative relation to the inclination of said 55 holder edges, guard extensions on said holders adapted to maintain material in the path of said blade, and means in said holders for engaging longitudinal warp wires in the 60 fabric to be cut.

4. A pile cutting device comprising a blade holder of U shaped cross section having an oblique end directed towards the pile, front and rear support rods for said holder, a blade in said holder oscillatably 70 mounted on the front support rod, said blade having an oblique straight cutting edge disposed in reverse relation to the oblique portion of said holder, and means for oscillating said blade whereby the cutting 75 edge is raised and lowered.

5. A pile cutting device comprising a blade holder of U shaped cross section having an oblique end directed towards the pile, said holder having a slot in its side 80 walls near its center, a rod movable in the mentioned slot, a knife in said holder having a recess in its lower edge suited to engage said rod, the cutting edge of said knife extending obliquely from the recess to its 85 extreme upper corner, a bar resting on the upper edge of said knife over the slot in said holder, rigid connections between the ends of said bar and said rod, and means for rocking said bar whereby a combined rearward sliding and downwardly turning shear motion is imparted to the cutting edge of 90 said knife.

In witness whereof I have signed my name to this application.

THEODOR BACHOFEN.
